UNITED STATES PATENT OFFICE

ROBERT VOSIKA AND LUDVIK VOSIKA, OF WILBER, NEBRASKA

BOTTLE-CLEANING APPARATUS

Application filed August 9, 1928. Serial No. 298,511.

The present invention relates to improvements in bottle washers and has for its principal object to provide a simple and efficient means for brushing and washing milk bottles, 5 fruit jars, and the like.

One of the important objects of the present invention is to provide a bottle washing apparatus that will save considerable time and labor and at the same time efficiently clean the 10 bottles.

A further object is to provide a bottle cleaning apparatus which includes a horizontally disposed water pipe from which extends upwardly a series of discharge tubes, over 15 which bottles to be cleaned are positioned in an inverted manner, means being provided for supporting the inverted bottles in proper position over the water discharge tubes, additional means being provided whereby the 20 interior of the bottles may be brushed, simultaneously with the washing thereof.

Still a further object is to provide a bottle cleaning apparatus of the above mentioned character which includes a means for supporting the bottle in any vertically adjusted 25 position with respect to the water discharge tube, so that the brushes associated with certain of the water discharge tubes may reach the bottom of the inverted bottle, to 30 facilitate proper cleaning thereof.

Still a further object is to provide a bottle cleaning apparatus of the above mentioned character which is simple in construction, inexpensive, strong and durable, and further well adapted to the purpose for which it is designed.

Other objects of the invention will become apparent as the description of the invention proceeds and when taken in connection with 40 the accompanying drawings.

In the accompanying drawings, forming a part of this application, and in which like reference characters designate like parts throughout the several views:

45 Figure 1 is a side elevation of the bottle cleaning apparatus embodying our invention;

Figure 1^a is an elevational view of a pipe adapted for use with the apparatus shown in Figure 1.

50 Figure 2 is a top plan view thereof.

In the drawings, wherein for the purpose of illustration is shown the preferred embodiment of our invention, the numerals 1 and 2, designate a pair of spaced supports, on which is mounted the elongated water pipe 3, the securing means for the water pipe being shown at 4. The diameter of the horizontally disposed water pipe 3 is relatively large, and the same has communication at its forward end with a water supply hose 5, through 55 the medium of the fitting 6. The water supply pipe or hose 5 may be connected to a faucet or a pump (not shown), in any appropriate manner.

An elbow 7 is associated with the other end of the horizontally disposed water pipe 3 and threaded in the upper end of the elbow is a plug 8, which plug may be removed to facilitate the attachment of the water discharge pipe 9, shown in Figure 1^a through 65 the elbow for communication with the water pipe 3, for use when the apparatus is attached to a pump, so that when the pressure becomes too great, the water may be passed out through the pipe 9.

Extending upwardly from the water pipe 3 at spaced intervals are the water discharge tubes 10, 11 and 12 respectively. In the present instance, three of such tubes are illustrated, although it is to be understood that 70 we do not wish to limit ourselves to the particular number of water discharge tubes that may be used. A pet cock 13 of the conventional construction is associated with the lower end of each water discharge tube for 75 controlling the supply of water from the pipe 3 to the tubes.

The invention further comprehends the provision of a pair of standards 14 and 15, respectively, that extend upwardly from the transverse supports 1 and 2 respectively, on one side of the horizontally disposed water pipe 3, and a longitudinally extending bar 16 is connected at its respective ends to the upper ends of the standards.

Appropriate braces 17 and 18 are provided for this frame like structure, whereby to render the same rigid.

A split circular band 19 is disposed around each of the water discharge tubes at the up-

per end thereof, and these bands are attached to the bar 16 as at 20, as clearly shown in Figure 2.

Apertured laterally extending parallel spaced ears 21 are formed on the free ends of each split band 19 and a bolt and thumb nut connection designated generally by the numeral 22 is associated with each pair of apertured ears for adjustably securing the band around a bottle that is disposed in an inverted position over the discharge tube. These bands are of such size as to accommodate bottles or jars of different diameters. An additional means for supporting the inverted bottles in position over the discharge tubes 10 is also provided, and the construction thereof will be presently described.

As shown very clearly in the drawings, a brush unit is associated with each of the water discharge tubes 11 and 12, and each of these brush units includes a vertically disposed stem 23, that extends along the side of each of the water discharge tubes 11 and 12, the lower end of each stem being secured to the water pipe, while the intermediate portion of each stem is secured to the respective water discharge tube, and the upper end of the stem extends beyond the upper end of each of the aforementioned water discharge tubes. The bristles 24 may be secured to the upper portion of each stem in any appropriate manner.

A pair of uprights 25 and 26 respectively have their lower ends secured to the top portion of the water pipe 3, adjacent the respective standards 14 and 15 and the upper ends of these uprights 25 are furthermore made rigid by connection to the adjacent standards through the medium of the offset cross pieces 40 27.

A pair of longitudinally extending strips 28 and 29 are disposed on opposite sides of the uprights 25 and 26 and also on opposite sides of the vertically extending water discharge tubes, the ends of these strips projecting beyond the outer side edges of the uprights and bolts and thumb nuts denoted generally by the reference character 30 are associated with the ends of these longitudinally extending spaced strips, whereby said strips may be secured in any vertically adjusted position upon the uprights so that the necks of the inverted bottles may rest on the upper edges of the strips. The provision of the vertically adjustable strips 28 that constitute bottle supporting means will permit the bottoms of the inverted bottles to be properly adjusted with respect to the brushes, so that the bristles can engage the bottoms of the bottles, as well as the inner or side walls thereof.

In use, the bottles to be cleaned are initially placed over water discharge tubes 11 and 12, and the petcocks 13 associated with

these particular tubes are opened, while the pet cock associated with the pipe or tube 10 is closed.

When the water is turned on the same will pass upwardly through the tubes 11 and 12, into the inverted bottles, and by manually turning the bottles, the brushes will thoroughly clean the interior thereof, after which the bottles are removed from the particular water discharge tubes and are then each placed over the water discharge tube 10, and when the pet cock for this particular tube is opened, fresh water will be forced upwardly into the bottle, for thoroughly rinsing the same, and when this operation has been completed, the bottles may be removed to be dried.

Also the outside of the bottles may be washed by holding the same directly over the upper ends of the water discharge tubes and the water ejected from said tubes will be forced against the outer surface of the bottles for cleaning the exterior thereof.

It will thus be seen from the foregoing description that we have provided a bottle cleaning apparatus that will save considerable time and labor and furthermore will at all times be positive and efficient in carrying out the purpose for which it is designed.

A bottle cleaning apparatus of the above mentioned character is particularly adapted for home use in cleaning milk bottles and fruit jars, although the apparatus can be used for other purposes.

The parts of our improved apparatus are so arranged as to permit the same to be properly adjusted and furthermore can be readily and easily cleaned whenever necessary.

While we have shown the preferred embodiment of our invention, it is to be understood that various changes in the size, shape and arrangement of parts may be resorted to, without departing from the spirit of the invention or the scope of the appended claims.

What we claim as new and desire to secure by Letters Patent is:

1. In a bottle cleaning apparatus of the character described, a pair of spaced supports, a horizontal water pipe extending across the spaced supports, a series of water discharge tubes extending upwardly from the pipe and having communication therewith, a valve associated with each of the tubes at the lower end thereof, a plurality of brush units, each arranged in close proximity to a water discharge tube for position within the interior of a bottle when the bottle is disposed in an inverted position over said discharge tube, a pair of uprights rising from said supports on one side of said water pipe, a horizontally disposed bar secured to the uprights, a plurality of split rings mounted on said horizontal bar, there being one split ring for each of said discharge tubes, said rings be-

ing arranged circumjacent their respective discharge tubes, means for securing the split rings in clamped relation about the bottles, a pair of elongated horizontally disposed strips 5 arranged on opposite sides of said tubes, means for supporting said strips in a vertically adjustable position with respect to said tubes, said strips being adapted to support the necks of the bottles disposed over said tubes.

10 2. In a bottle cleaning apparatus of the class described, a water pipe, a support for said pipe, said pipe being provided with a plurality of valve controlled discharge tubes 15 projecting upwardly therefrom, a frame structure, means for mounting said frame structure to one side of said pipe, said frame structure being provided with a plurality of split rings, means for mounting said rings 20 on the frame structure, said rings being arranged circumjacent said discharge tubes, for engagement with the bottles disposed in an inverted position over said tubes, means for securing the ends of said split rings 25 whereby said rings may be clamped about the bottles for holding the bottles in a predetermined inverted position over said tubes, and a plurality of brush members each arranged in parallelism to and adjacent a tube 30 and extending beyond the discharge end thereof, for disposition within the bottle inserted over said tube, and adjustable means upon which the necks of the bottles rest for supporting the bottles in proper position 35 over the said tubes and brush members.

In testimony whereof we affix our signatures.

LUDVIK VOSIKA.
